(57) **CLAIM**

The ornamental design for a trinket, as shown and described.

DESCRIPTION

FIG. 1 is a front perspective view of a trinket; and, FIG. 2 is a bottom perspective view of the trinket with removed base.

The designs are trinkets for advertising in the form of balls with magnetic bases; the variants include baseballs; in some variants the ball trinkets are empty and their bases can be removed, creating a small storage space inside.
